UNITED STATES PATENT OFFICE.

JOSEPH F. SCHULTHEISS, OF WEEHAWKEN, NEW JERSEY.

GAME APPARATUS.

1,379,218.

Specification of Letters Patent. Patented May 24, 1921.

Application filed December 22, 1919, Serial No. 346,506. Renewed March 26, 1921. Serial No. 455,979.

To all whom it may concern:

Be it known that I, JOSEPH F. SCHULTHEISS, a citizen of the United States, residing at Weehawken, in the county of Hudson and State of New Jersey, have invented certain new and useful Improvements in Game Apparatus; and I do declare the following to be a full, clear, and exact description of the invention, such as will enable others skilled in the art to which it appertains to make and use the same.

This invention relates to an improved game-apparatus.

The object of my invention is to provide a game-apparatus including an open frame carrying at one end a plurality of pins which are adapted to be rocked by a ball which is rolled from the other end of the frame.

Another object is to provide a game-apparatus of the class described in which the amount of material necessary in the manufacture of the board is reduced to a minimum.

With the above and other objects in view the invention consists of certain novel features of construction and the combination and arrangement of parts as will be more fully described and claimed.

I attain these objects by constructing the game-board as illustrated in the accompanying drawings in which:

Figure 1 is a top plan view of the game-board;

Fig. 2 is a section taken on the plane of line 2—2 of Fig. 1;

Fig. 3 is a section taken on the plane of line 3—3 of Fig. 1; and

Fig. 4 is a section taken on the plane of line 4—4 of Fig. 1.

Similar reference numerals designate similar parts throughout the several views.

In constructing this improved game-apparatus I provide a substantially rectangular frame including two long side-bars 1, connected together at their ends by cross-bars 2 and provided at one end with a floor board 3 which terminates at a point adjacent said end. At this end is also provided a short strip 4 which coacts with the floor board 3 in forming a pocket for reception of balls to be used in connection with this game-apparatus.

Adjacent the other end of the frame is a vertical transverse partitioning strip 5 in the lower edge of which is formed a plu-

rality of spaced notches which provide archways or openings through which a ball may be rolled to operate parts of the apparatus to be described.

Mounted transversely of the frame and at a point between the partitioning strip 5 and the adjacent end of the frame is a shaft 6, the outer ends of which are bent downwardly and removably received in sockets formed in the upper edges of the side-bars 1.

1. A plurality of rocking pins 7 are mounted between their ends on said shaft and are spaced by blocks 8 or by any other suitable or preferred means, each of said pins being longitudinally alined with one of the archways or openings in the partitioning strip 5. As illustrated in Fig. 2 these pins are preferably provided with shaft-receiving openings positioned at a point slightly below the central point so that there will be a tendency for the upper end to topple over, it being understood that this positioning of the shaft opening will leave the greater part of the pin positioned above the shaft.

Spaced horizontally and vertically from the shaft 6 is a pair of stop-bars 9 whose ends 10 are bent downwardly and removably received in sockets formed in the upper edges of the side-bars 1.

In using this game apparatus the frame is adapted to be placed upon a table or the like, said table forming the bottom of the apparatus, and before play is started the pins are positioned as illustrated in full lines in Fig. 2 in which the pin is shown leaning against the outer stop-bar 9. A ball is rolled from the opposite end of the frame and is supposed to pass through one of the openings in the partition strip 5 and strike the lower end of one of the pins 7 and rock it to the position shown in dotted lines in Fig. 2. Each of these pins carries a different number and it is understood that the player is to be credited with the total of the numbers carried by the pins which he rocks or knocks over by rolling the balls through the openings as set forth. The lower ends of the pins are preferably provided with cushioning members 11 so that when the former are rocked said lower ends will not strike the adjacent end board and create unnecessary noise.

Secured to the end board adjacent the pins is an eye-screw 12 which is used to hang the game-apparatus on a nail or other

support, the other end being simultaneously used to contain the balls as heretofore described.

From the foregoing description, taken in connection with the accompanying drawings, the construction and operation of this invention is readily understood without requiring a more extended explanation.

Various changes in the form, proportion and minor details of construction may be resorted to without departing from the principle or sacrificing any of the advantages of the claimed invention.

I claim:

15. 1. A game apparatus comprising a guideway, a pivot rod extending transversely of the guide-way adjacent one end, rocking pins pivotally mounted upon the pivot rod with the rod extending through each pin at 20 a point below the vertical center of the pin to normally position the pin out of the vertical position, and abutment rods extending transversely across the guide-way in front of and to the rear of the pivot rod for engagement by the rocking pins to support the rocking pins in an inclined position.
25. 2. A game-apparatus comprising a pair of side-bars spaced apart to form a guideway, a plurality of vertically disposed rocking pins arranged in a transverse row across and adjacent one end of said guideway, a pair of transversely disposed stop bars having their ends supported on said side-bars, said stop-bars being spaced horizontally and 30 vertically from the pivotal points of said pins to limit the movement of the latter, said pins being adapted to be struck and rocked by a ball rolled down the guideway.
35. 3. A game-apparatus comprising a pair of 40 side-bars, spaced apart to form a guideway,

and a plurality of vertically disposed rocking pins arranged in a transverse row across and adjacent one end of said guideway, said side-bars having sockets spaced horizontally from each side of the pins, a pair of stop-bars arranged in parallel relation across said guideway and having their ends bent down and removably received in said sockets, said bars being spaced horizontally and vertically from the pivots of the pins and being 45 adapted to limit the rocking movement of the latter.

4. A game apparatus comprising a guideway, counters pivotally mounted adjacent one end of the guide-way and extending 55 transversely of the same and normally positioned out of a vertical position, and abutment rods extending transversely of the guideway in front and to the rear of the counters and adapted for engagement by 60 the counters to support the counters in an inclined position.

5. A game-apparatus comprising a pair of side-bars spaced apart to form a guideway, a vertical transverse partition strip adjacent one end of the guideway, said strip having a plurality of spaced openings along its lower edge, a horizontal transverse shaft disposed between said partition and the adjacent end of the guideway, a plurality of 65 rocking pins mounted between their ends on said shaft, and a pair of stop-bars spaced horizontally and vertically from said shaft to limit the movement of said pins, said pins being adapted to be struck and rocked 70 by balls rolled through said openings.

In testimony whereof I have hereunto set my hand.

JOSEPH F. SCHULTHEISS.
